ATTORNEY

UNITED STATES PATENT OFFICE

ANTHONY G. M. MICHELL, OF MELBOURNE, AUSTRALIA

VISCOMETER

Application filed July 20, 1928. Serial No. 294,202.

This invention relates to an improvement in viscometers of the type described in Patent No. 1,398,878.

The viscometer disclosed in the patent referred to comprises two closely fitting parts, namely, a cup and a ball, the former constituting a seat for the latter. A film of fluid, the viscosity of which is to be measured, is placed in the cup before the ball is seated 10 therein and the weight of the ball determines the time of operation of the instrument. The ball being of constant weight, the time of operation varies in direct proportion to the viscosity of the fluid under test.

15 The present invention has for its object to provide means whereby the same viscometer may be applied to test fluids having a wide range of viscosities without the time of operation being in any case either inconveniently 20 long or too short to enable a result of the required degree of accuracy to be obtained.

Further objects of the invention will appear from the following specification taken 25 in connection with the drawings, which form a part of this application, and in which

Fig. 1 is an elevational view, partly in section, showing a viscometer constructed in accordance with the invention, having a supplemental weight; and

30 Fig. 2 is a plan view of the supplemental weight.

The invention briefly described consists of a weight adapted for use in supplementing the weight of the ball in a viscometer comprising a cup and ball, the weight being so constructed and arranged that it can be detachably carried by and supported on the ball.

Further details of the invention will appear 40 from the following description.

In the embodiment of the intention illustrated, the weight 10 consists of an annulus of metal or other solid material. Its inner 45 surface 12 fits the ball 13 in such manner that when the viscometer is suspended for making a test, as shown in Fig. 1 and as described in the cited patent, the ball adhering to the cup 14 by means of the film 15 of the fluid under test, the annular weight is supported upon

the ball and its center of gravity coincides approximately with the center of the ball.

In the preferred form shown in the drawing, the peripheral surface 16 of the annulus is cylindrical and the upper and lower surfaces 17 and 18 flat, the thickness of the annulus being less than the diameter of the ball, while the internal surface 12 is conical, being at the lower end of greater, and at the upper end of less diameter than the ball whereby 60 the ball is unable to pass through the annulus.

The apical angle of the conical surface is preferably about 30°, so that the ball may be temporarily and detachably affixed in the annulus by their frictional contact, and the ball and annulus together may be temporarily manipulated as one piece in the operation of making a test as described in the cited patent.

The weight of the annulus is preferably 70 an integral multiple of the weight of the ball, it being desirable that the period of time during which the ball is held suspended and the period of time during which the ball and weight are held suspended should 75 bear a simple numerical relation to one another.

Although one specific embodiment of the invention has been particularly shown and described, it will be understood that the 80 invention is capable of modification and that changes in the construction and in the arrangement of the various cooperating parts may be made without departing from the spirit or scope of the invention, as expressed 85 in the following claims.

What I claim is:

1. A viscometer comprising a cup and a ball having interfitting surfaces, said cup having a handle connected thereto, and a supplemental weight detachably carried by the ball and supported directly thereon.

2. A viscometer comprising a cup and a ball having interfitting surfaces, and a supplemental weight detachably carried by the ball and supported thereon, said supplemental weight having a tapered opening therethrough, the smaller end of the opening having a diameter less than the diameter of the ball.

3. A viscometer comprising a cup and a ball having interfitting surfaces, and an annular weight adapted to surround the ball and to be supported directly thereon.
4. A viscometer comprising a cup and a ball having interfitting surfaces, an annular weight surrounding and detachably affixed to the ball, and having its center of gravity substantially coincident with the center of said ball.
5. A viscometer comprising a cup and a ball having interfitting surfaces, an annular weight adapted to be attached to the ball of the viscometer by engagement of the inner 10 surface of the weight with the surface of the ball.
6. A viscometer comprising a cup and a ball having interfitting surfaces, and an annular weight having a conical inner surface 20 tapering from a diameter greater than the diameter of the ball of the viscometer to a diameter less than the diameter of said ball whereby the weight may be supported from the ball when the ball is inserted in the conical opening of the weight.

In witness whereof, I have hereunto set my hand this 18th day of July, 1928.

ANTHONY G. M. MICHELL.
